(57) **CLAIM**

The ornamental design for a shoe, as shown and described.

DESCRIPTION

FIG. 1 is a perspective view of the shoe.

FIG. 2 is a front view of FIG. 1.

FIG. 3 is a rear view of FIG. 1.

FIG. 4 is a top plan view of FIG. 1.

FIG. 5 is a bottom plan view of FIG. 1.

FIG. 6 is a left side view of FIG. 1; and,

FIG. 7 is a right side view of FIG. 1.

The entire shoe illustrated in FIGS. 1-7 is made of transparent material such as glass or plastic so that the entire shoe is transparent, with the shoe having a plurality of triangular-shaped facets.

The broken lines in the drawings are for illustrative purposes only and form no part of the claimed design.
